(57) **CLAIM**

The ornamental design for a decorative lighting apparatus, as shown and described.

DESCRIPTION

FIG. 1 is a perspective view of a decorative lighting apparatus according to the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown on the drawings are for illustrative purposes only and form no part of the claimed design and the portions of the device shown broken-away are to depict indeterminate length.
